GROUND CLAMP

Henry H. Merriman, Jackson, Mich., assignor to
 Harry D. Boardman, Jackson, Mich., as
 trustee

Application November 7, 1942, Serial No. 464,903

3 Claims. (Cl. 173—273)

1

The present invention relates to welding clamps and more particularly to C clamps adapted to be clamped to some part of work to be arc welded for the purpose of making a ground connection.

Clamps of the type to which the present invention relates have been heretofore known, but have not been wholly satisfactory due to the fact that it was not possible to make a good ground connection and the clamps were not flexible enough in operation to meet all of the requirements arising in use. The clamp according to the present invention fulfills the requirements for an efficient welding ground in that it provides an efficient ground connection and is adaptable to a variety of uses. Furthermore in special cases it may be used as a ground connection by merely laying the same against the member to which it is to be grounded without endangering or in any way harming the operative portion of the clamp.

An object of the invention is to provide a ground clamp having a substantial area of contact with the member to which it is attached.

Another object of the invention is to provide a ground clamp of the character described having a serrated contact surface.

Still another object of the invention is to provide a ground clamp having a contacting lug which is insulated from the clamp body.

A further object of the invention is to provide a ground clamp of the character described provided with a contacting lug which is attachable to the clamp body in a plurality of relationships.

A still further object of the invention is to provide a ground clamp of the character described having a contacting lug provided with an attaching tab which has clearance from the member to which the clamp is secured.

These and other objects residing in the arrangement, combination and construction of the parts will be apparent from the following specification when taken with the accompanying drawings, in which

Fig. 1 is a side elevation of one embodiment of the invention,

Fig. 2 is a section on the line II—II of Fig. 1,

Fig. 3 is a plan view of the contacting lug of the clamp disclosed in Figs. 1 and 2, and

Fig. 4 discloses the invention associated with a different form of clamp to that disclosed in Fig. 1.

Referring particularly to the drawings, the reference character 1 indicates a C clamp body of a conventional construction although it will be understood that any particular type of clamping frames desired may be employed. The frame is

2

provided with an adjustable clamping bar 2 having a handle 3 and a combination quick feeding slip structure 4 associated with the clamping screw 5. The structure 4 may be of any desired design, but preferably corresponds to that disclosed in the co-pending application of Ralph N. Richards, Serial No. 377,409, filed February 5, 1941, issued as Patent No. 2,313,361 on March 9, 1943. Disclosed at the working end of the bar 2 is a foot 6 having a conventional ball and socket connection 7 with the bar 2 for permitting a limited rocking movement of the foot 6. The foot 6 constitutes one clamping face of the clamp. The second clamping face is constituted by a contact lug 8. The contact lug 8 is secured to the clamp body 1, on a suitable lug supporting portion, by a screw 9 passing through a bore 10 in the clamp body 1 and having a threaded engagement with the contact lug 8. The contact lug 8 is provided with a shoulder 15 which as shown in the drawings is complementary to an upstanding shoulder 16 on the clamp body 1 adjacent to the lug supporting portion. The shoulder 16 serves as a driving shoulder so that when the clamp is secured to a member 17 for example, and oscillated about an axis parallel to the axis of the bar 2, the shoulder 16 drives the contact lug 8 causing the same to oscillate also.

The contacting surface 18 of the contact lug 8 is provided with a plurality of grooves 19 in the surface thereof for the purpose of facilitating the cleaning of the member 17 when the clamp is secured thereto. The clamp is secured to the member 17 by axially moving bar 2 and with it the foot 6 until the foot 6 bears against the member 17. The member 17 is urged then against the contact face 18 of contact lug 8 and the handle 3 is rotated to clamp the member 17 between the foot 6 and the contact surface 18. An oscillating of the clamp about an axis parallel to the axis of the bar 2 will cause the edges of the grooves 19 to scrape the surface of the member 17. This scraping will cause paint, dirt, dust particles and the like to be removed from the surface of the member 17 and they will drop into the grooves 19 thereby providing a good clean ground connection between the member 17 and the contact lug 8.

The screw is insulated from the clamp body 1 by an insulating bushing 20 and an insulating washer 21. The contact lug 8 is insulated from the body 1 by an insulating plate 22 placed between the bottom of the lug 8 and the clamp body 1 and an insulating plate 23 placed between the shoulder 16 of the clamp body 1 and the shoul-

der 15 of the lug 8. The insulating plate 22 is retained in its position by the screw 9 and the insulating plate 23 is retained in position by insulating pins 24 extending through the insulating plate 23 and into the clamp body 1 as shown particularly in dotted outline in Fig. 1.

The contact lug 8 is provided with a ground wire connecting tab 28 having a bore 29 therein for the purpose of receiving a suitable clamping bolt not shown. The tab 28 is arranged so that the upper surface 30 thereof is spaced downwardly from the contact surface 18 of the lug so that the head of a connecting bolt 31 shown in dotted outline in Fig. 1 will clear the member 17.

The lug 8 is so positioned as shown in Fig. 1 with respect to the clamp body 1 that the tab extends to the right as shown in Fig. 1. One feature of the invention is that the lug 8 is so shaped that the tab 28 may extend either forwardly or rearwardly or to the side of the clamp body 1 with respect to its position as shown in Fig. 1. To achieve these results, the lug 8 is provided with shoulders 32 and 33 which are spaced the same distance from the threaded bolt receiving opening 34 as the shoulder 15 so that any one of the shoulders 15, 32 or 33 may be arranged in complementary relation to the shoulder 16 of the clamp body 1 to enable the shoulder 16 to act as a driving shoulder when the clamp body 1 is oscillated about an axis parallel to the axis of the bar 2 as hereinabove described. While the lug 8 as shown in the drawings is square to achieve the results specified, it will be understood that the same result may be achieved by shapes other than square so long as the spacing between the shoulders and the opening 34 remains the same.

With this construction, the polygonal or substantially square contact lug 8 having the ground wire connecting tab 28 extending substantially laterally or radially therefrom can be mounted in the recessed or cut away lug supporting portion of the clamp body for positioning of the connecting tab to extend laterally or radially in any one of three different positions, substantially 90° apart. In each position, the upstanding shoulder 16 on the clamp body serves to retain the contact lug 8 with the connecting tab 28 extending or projecting in the desired direction, and against swinging or shifting movement. The insulating plate 23, being interposed between the shoulder or face 15 of the lug 8 and the upstanding shoulder 16 of the clamp body 1 assures proper insulation of contact lug 8 when in each of its settings.

The form of the invention disclosed in Fig. 4 is the same as that disclosed in Figs. 1, 2 and 3 with the exception that instead of having a slip clamping bar 2 there is provided the conventional threaded clamping bar 35, thus illustrating the fact that the features of the invention are

not applicable to any one particular type of clamp.

Having thus described my invention, what I desire to secure by Letters Patent and claim is:

5 1. A welding clamp comprising a clamp body having clamping means at one end and a bore at the other end with a shoulder upstanding adjacent to the bore, a polygonal contact lug with which the clamping means cooperates to clamp and electrically connect a member to be welded, said lug having a registering bore opening and being provided with a laterally extending connecting tab, and means received in the bores mounting the contact lug on the clamp body with 10 a selected side thereof in juxtaposition to the shoulder.

2. A welding clamp comprising a substantially C-shaped clamp body having a contact lug supporting portion at one end with an upstanding shoulder adjacent thereto, an adjustable clamping bar at the other end of the body, a contact lug having a plurality of faces and provided with a laterally extending wire connecting tab, and means adjustably securing said lug on the supporting portion of the body with a selected face of the lug adjacent and complementary to the first-named shoulder.

3. A welding clamp comprising a substantially C-shaped clamp body having a contact lug receiving portion at one end and provided with an upstanding shoulder adjacent to the contact lug receiving portion, clamping means at the other end of the body movable toward and away from the lug receiving portion, a contact lug of 30 substantially polygonal form with a plurality of side faces and with an end face serving as a contact surface, a wire attaching tab projecting laterally from one of the side faces of said contact lug, said tab being in a plane spaced 35 away from the plane of the contact surface of said lug, and means for mounting the contact lug on the lug receiving portion of the clamp body with the connecting tab extending in a desired direction and with a side on the contact lug in 40 juxtaposition to the shoulder, whereby the contact lug is held against twisting movement and 45 a wire joined to said connecting tab will be held out of the plane of the contact face of the connecting lug.

50 HENRY H. MERRIMAN.
